CLAIM

The ornamental design for an incense holder, as shown and described.

DESCRIPTION

FIG. 1 is a perspective view of an incense holder of the present invention.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1; and,

FIG. 8 is a perspective view showing a state of use of the incense holder of FIG. 1 which holds an incense. The broken lines in the figure are for the purpose of illustrating environmental structure and form no part of the claimed design.
